MACHINE FOR GRINDING AND SUPERFINISHING BARREL-SHAPED ROLLERS AND THE LIKE

Hans Modler, Aschaffenburg, Germany

Application July 28, 1954, Serial No. 446,259

8 Claims. (Cl. 51—108)

This invention has reference to a machine for the centreless grinding and honing, or superfinishing, of the crowned surfaces of barrel-shaped antifriction rollers and similar bodies, and it particularly relates to a machine for this purpose, having a concavely shaped revolute grinding wheel, or a reciprocating superfinishing tool respectively, and a cooperating regulating wheel, between which the workpieces are rotated and, thereby, operated upon and fed through the machine in a revolute carrier substantially resembling the shape of the working throat of the machine at its work-presenting section.

In the known grinding devices of this type the support of the work pieces which, for the sake of simplicity, will hereinafter be referred to as rollers, on their carriers has not been able to meet the requirements of practice. It was unstable and the rollers, being supported on their great circles only, could deviate in various directions and were even able to edge between the grinding and regulating wheels. For these and other reasons it has been exceedingly difficult up to the present to obtain that accuracy in finishing crowned or barrel-shaped roller surfaces which, however, is of paramount importance in the construction of antifriction bearings.

It is, therefore, the principle object of the invention to remove these discrepancies and to provide a device which will be simple in construction and effective in use and in which rollers of crowned or barrel-shape can be ground and finished to the highest degree of accuracy.

Another object is the provision of a device in which means are provided for guiding the rollers through the machine and for thereby holding them revolutely but bodily immovable on their carrier to be acted upon by the operating tools of the machine.

A further object of the invention rests in the provision of means for continuously feeding the rollers into the machine and for automatically rejecting them from the carrier after treatment.

A still further object is the provision, in conjunction with or in addition to a grinding device, of a honing or superfinishing device for the centreless honing of the crown surfaces of the rollers after grinding, and which honing device shall be constructed on substantially similar lines as the grinding device, particularly in regard to the feeding of the rollers and presenting them to the superfinishing tool.

With these and other objects in view the invention consists in the provision of a carrier or work rest for the rollers in the shape substantially of a circular cage, which cage is provided around its circumference with individual chambers open to the outside; the said carrier being rotated at a comparatively slow speed in the feeding direction of the rollers, which are thereby presented to both the grinding wheel, or the honing tool respectively, and the regulating wheel.

By means of the individual chambers just referred to and which are suited to the crowned shape of the rollers and adapted laterally to engage between parallel end walls of the same, several rollers can be presented to the

operating tools at the same time and in a manner which prevents any side movement, tipping or the like, of the rollers while they are being acted upon during their passage through the machine.

5 The invention is illustrated in the accompanying drawings by way of example.

Fig. 1 is a longitudinal vertical section through the grinding device on the line I—I of Fig. 2 as seen in the direction of the arrow.

10 Fig. 2 is a plan view of Fig. 1 as seen in the direction of the arrow II of that figure.

Fig. 3 is a cross section similar to Fig. 1 of the honing or superfinishing device, and

15 Fig. 4 a plan view similar to Fig. 2 of the device shown in Fig. 3.

In these figures, particularly in Figs. 1 and 2, the grinding wheel of a plain grinding machine suitable for circular work is denominated by the numeral 1 and the regulating wheel by 2. The latter is journaled with its shaft 3 between the centre points of the grinding machine which, however, is not shown in the drawings with the exception of some parts which will be referred to in connection with Fig. 3. The revolute grinding wheel 1 is provided over its circumference with a concave grinding surface, while 20 the regulating wheel 2 is of spherical shape as shown in Fig. 2. Both wheels rotate in mutually opposite direction as indicated by the arrows.

Arranged on a conical head between the two wheels 1 and 2 is a circular cage 4 around the circumference 30 of which a number of individual chambers 5 is provided which open outwardly and in which the rollers are supported with their parallel end walls in intimate contact with the side walls of the chambers 5. These side walls prevent axial and tipping movement of the rollers, which 35 are further stabilized in their position on the carrier 4 by the bottom of each of the chambers being recessed in the middle as at 5', so that the rollers are supported on two points and, in this way, further resist any tendency of tipping or edging.

40 Cage 4 together with its conical head is keyed or otherwise fixed to the upper end of a shaft 7 which is driven by a worm gear 8 at its lower end and by which it is rotated together with the rollers 6 engaged therein at a slow speed in comparison with the rotary speed of the wheels 1 and 2.

45 The common turning axis of the shaft 7 and of the cage 4 is positioned so as to intersect a plane which passes through the turning axes of the grinding wheel and of the regulating wheel at an acute angle β , whereby it is possible to arrange the shaft 3 of the regulating wheel so as to approach the cage 4 very closely, as will be seen from Fig. 1. The spherical surface of the regulating wheel 2 hereby dips into the excavation 13 of the cage 4 and its supporting head. The worm gear 8 is preferably enclosed in a gear box 8' which is fitted to the machine bed 7' in which also the shaft 7 of the cage 4 is arranged to rotate.

50 The substantially barrel-shaped rollers 6 are fed into the chambers 5 of the cage 4 through a channel or race-way 9, whereby the introduction of the rollers can be facilitated by the outer portions of the separating walls of the chambers 5 being slightly rounded. After the rollers have been operated upon during the slow rotation of the cage 4 in the working throat 6' between the grinding wheel 1 and the regulating wheel 2 they are discharged by coming into contact with an inverted cone 12 on shaft 3 adjacent the regulating wheel 2 and rotated therewith, whereby the rollers are lifted and prized out. It will 55 be seen from Fig. 2 that a circle passed around the rollers 6 in the cage 4 has its centre at C with the radius R. The concave curvature of the operating surface of the grinding wheel is centered at C' and its radius R' is of the same

60 65 70

length as the radius R so that the rollers are automatically ground true to the curvature of the grinding wheel without the risk of their deviating to either side because of their being confined in position by the fixed walls of the chambers 5.

After the rollers have been ground in the manner described they are honed, or superfinished, in the same or similar manner on the honing device illustrated in Figs. 3 and 4. As in the former case a regulating wheel 15 and a discharge cone 16 is provided on the shaft 14 of the regulating wheel, which shaft may be arranged between the centre points of a plain grinding machine as in the device shown in Figs. 1 and 2. The cage 17 for the rollers to be honed resembles the aforescribed cage 4 and is also provided with a plurality of individual chambers 18 within which the rollers 6 are confined so as to protrude slightly beyond the periphery of the cage 17. The latter is keyed to the shaft 20 adapted to be rotated by the worm gear 23 in a bearing block 22 of the machine bed 21.

Turnable upon the bearing block 22 and an intermediate pin bearing 25 is a rocking lever 26 carrying at its free end a member 27 adapted to reciprocate a slide 28 with the honing stone 30 fastened to it. Vibration is imparted to this system by an oscillator or the like 31 over a ball head socket 32, which movement is then transformed into a circular reciprocating movement by the said lever 26 and member 27 and transmitted thereby over the slide 28 to the honing tool 30. This tool, therefore, also reciprocates in a circular path true to the surface of the rollers 6 which are thus superfinished in the radius R as has been described with reference to Figs. 1 and 2.

Rotation is imparted by the regulating disc 15 and the pressure wheel 33 to the rollers 6. The pressure wheel may be coated by a sheet of vulcanite 34 or the like. Admission of the rollers into the chambers 18 is effected over a raceway 35, as in Figs. 1 and 2, and the discharge by the discharge cone 16 on shaft 14.

What I claim is:

1. In a machine for the centerless shaping of the curved outer surfaces of crowned rollers, such as barrel-shaped antifriction rollers and the like, by means of a surfacing tool and having a revoluble circular cage member serving as a work rest, a plurality of roller-receiving chambers spaced around the circumference of said circular cage member open to the outside and with mutually parallel side walls, and a regulating wheel in contact with the rollers while they are being operated upon by the surfacing tool, a rotary shaft for the said circular cage member disposed at an angle to the said surfacing wheel, a rotary shaft for the said regulating wheel at substantially right angles to the shaft of the cage member, and an axially disposed excavation in said cage member affording space for the rotation therein of the lower part of the regulating wheel, said circular cage member being arranged to revolve below the shaft of the regulating wheel so as to allow for the free rotation of said cage member underneath the driving shaft of the regulating wheel.

2. A machine for operating on the surfaces of crowned roller as set forth in claim 1, in which the axis of rotation of the cage member and the axis of rotation of the regulating wheel intersect each other.

3. A machine for operating on the surfaces of crowned rollers as set forth in claim 1, comprising means for discharging the rollers from their chambers, said means consisting of a discharge cone on the shaft of said regulating wheel adjacent the said wheel and revoluble therewith and by means of which the rollers on coming into con-

tact therewith are lifted and prised out of their chambers.

4. In a machine for the centerless shaping of the curved outer surfaces of crowned rollers, such as barrel-shaped antifriction rollers, by means of a surfacing tool and having a revoluble circular cage member serving as a work rest, a plurality of roller-receiving chambers spaced around the circumference of said circular cage member, parallel side walls to the said chambers, and means for maintaining the rollers in contact with said surfacing tool during operation, a regulating wheel of substantially spherical formation, a shaft for driving said regulating wheel in contact with the rollers to be ground, a surfacing tool having a concave working edge of arc-shaped formation, a circular cage member revoluble in cooperation with said concave surfacing edge at right angles to the shaft of said regulating wheel, the roller-receiving chambers being so spaced around the circumference of said cage member as always to move a plurality of rollers along said surfacing edge thereby to enable a continuous operation on the said rollers, and a two-point support in each of the said chambers for centering the rollers in conjunction with the parallel side walls of the chambers in relation to the surfacing tool, said circular cage member having its shaft disposed at an angle to the surfacing tool and ending below the shaft of the regulating wheel to allow for the free rotation of the cage member underneath the said shaft.

5. In a machine for operating on the surfaces of crowned rollers as set forth in claim 4, in which the said concave-edged surfacing tool is a substantially plane superfinishing stone, means for imparting to the said stone a reciprocating arcuate motion, comprising, a member producing a linear motion and a pivoted lever transmitting said linear motion into a circular motion along the surfaces of the consecutive rollers as they are moved along the said concave working edge of the surfacing tool in cooperation therewith.

6. In a machine for operating on the surfaces of crowned rollers, such as barrel-shaped antifriction rollers and the like, by means of a reciprocating superfinishing member, a substantially plane surfacing tool, a concave working edge of arc-shaped formation on the said tool, a work rest comprising a circular head, individual chambers around the circumference of said head for the accommodation of said barrel-shaped rollers while they are being operated upon, a regulating wheel of substantially spherical formation contacting with said rollers at one side thereof, parallel side walls to the said individual chambers, a substantially vertical shaft for rotating said circular head, a pressure roller contacting with said barrel-shaped rollers at approximately the other side thereof, a slide carrying said reciprocating superfinishing member, a device for producing linear reciprocating movement, a pivoted lever in connection with said slide and pivotally arranged on the vertical shaft of said circular head for transforming the linear reciprocating movement of the slide carrying said superfinishing member.
